UNITED STATES PATENT OFFICE

149,872

DESIGN FOR AN ICE CREAM DISPENSING UNIT

William M. Harris, Greenwich, Conn., assignor to
National Dairy Products Corporation, New
York, N. Y., a corporation of Delaware

Application May 24, 1947, Serial No. 139,259

Term of patent 14 years

(Cl. D80—2)

To all whom it may concern:

Be it known that I, William M. Harris, a citizen of the United States, residing in Greenwich, in the county of Fairfield and State of Connecticut, have invented a new, original, and ornamental Design for Ice Cream Dispensing Unit, of which the following is a specification, reference being had to the accompanying drawings, forming a part thereof, in which

Fig. 1 is a perspective view of an ice cream dispensing unit embodying my new design;

Fig. 2 is a front elevational view;

Fig. 3 is a side elevational view; and

Fig. 4 is a top plan view thereof.

I claim:

The ornamental design for an ice cream dispensing unit, as shown.

WILLIAM M. HARRIS.
